CLAIM

The ornamental design for the actuator overcap, as shown and described.

DESCRIPTION

FIG. 1 is a perspective view of the actuator overcap of our invention;

FIG. 2 is a front view of the actuator overcap of our invention;

FIG. 3 is a right side view of the actuator overcap of my invention, the left side being a mirror image of the right side;

FIG. 4 is a top view of the actuator overcap of my invention; and,

FIG. 5 is a back view of the actuator overcap of my invention.

The bottom view is not shown nor seen in normal use and does not form part of our claimed design.
